UNITED STATES PATENT OFFICE

160,533

SALT SHAKER OR SIMILAR ARTICLE

John Pinkos, Attleboro, Mass.

Application August 23, 1949, Serial No. 4,663

Term of patent 7 years

(Cl. D44—22)

To all whom it may concern:

Be it known that I, John Pinkos, a citizen of the United States, residing at 17 James Court, Attleboro, in the county of Bristol and State of Massachusetts, have invented a new, original, and ornamental Design for a Salt Shaker or Similar Article, of which the following is a specification, reference being had to the accompanying drawing, forming a part hereof.

Fig. 1 is a side view in perspective of a salt shaker or similar article, showing my new design; and

Fig. 2 is a plan view of the same.

I claim:

The ornamental design for a salt shaker or similar article, as shown.

JOHN PINKOS.
